PROCESS AND APPARATUS FOR PRODUCING LUMINOUS EFFECTS

Filed April 18, 1927

UNITED STATES PATENT OFFICE

HERMAN J. FANGER, OF OAKLAND, CALIFORNIA, ASSIGNOR, BY DIRECT AND MESNE ASSIGNMENTS, OF ONE-THIRD TO EDMUND R. WEEK, JR., AND ONE-THIRD TO EDMUND R. WEEK, SR., BOTH OF OAKLAND, CALIFORNIA

PROCESS AND APPARATUS FOR PRODUCING LUMINOUS EFFECTS

Application filed April 18, 1927. Serial No. 134,711.

This invention relates to the production of luminous effects by electrical currents passing through rarefied gases. These effects have been noted a long time ago by Geissler, 5 who is popularly credited with their discovery. In his experiments, use was made of rarefied air; but more recently, it has been found that other kinds of gases produce highly desirable effects. For example, some 10 of the rare gases occurring in air, such as neon, argon and helium have been used to secure brilliant color effects; as well as mercury vapor. In all these forms it has been necessary to impress high voltages across the 15 electrodes of the tube, of the order of 15,000 volts, in order to secure a luminous flow of current that could be used for forming words, letters or borders in advertising, and for other purposes.

20 The cost of advertising equipment using these tubes is rather high, due to the use of the high voltage, and also to the careful construction of the electrodes forming the terminals of the luminous discharge. It has been found that the length of the tube cannot be increased beyond a definite value if the luminosity is to persist. This means that 25 a pair of electrodes are needed for each unit of length. It is one of the objects of my invention to make it possible to reduce the 30 number of electrodes that is needed for a given pattern traced by tubes strung out one after the other.

In the past it has also been customary to 35 secure an even, invariant light, such as blue or red. It is another object of my invention to make it possible to secure a rainbow effect in the tube, in which there is a constant interplay of colors, streaming through the 40 tube in succession. In this way, a much more attractive display is secured than could be obtained in the ordinary type of tube.

45 My invention possesses many other advantages, and has other objects which may be made more easily apparent from a consideration of several embodiments of my invention. For this purpose I have shown a few forms in the drawings accompanying and forming part of the present specification. I shall now 50 proceed to describe these forms in detail,

which illustrate the general principles of my invention; but it is to be understood that this detailed description is not to be taken in a limiting sense, since the scope of my invention is best defined by the appended claims. 55

Referring to the drawings:

Figure 1 is a schematic diagram showing one form of my luminous tube system; and

Fig. 2 is a diagram of another form of my invention.

In Fig. 1 I show a tube 11, partly broken away (to indicate that its length is indefinite), through which a luminous stream is caused to flow. This tube can be formed into letters or parts of letters in the well-understood manner. It has three electrodes—two end electrodes 12 and 13, and a center electrode 14. All three are sealed in the glass wall of the tube. Both end electrodes 12 and 13 are connected to one side of a high potential source, such as the negative side; and the central electrode 14 is connected to the other side. The electric current in tube 11 thus flows in two directions from electrode 14, towards the ends of the tube. The high potential of the source is impressed on each half of tube 11; therefore this tube can be made twice as long as those using only two electrodes. It is thus possible to use only three electrodes instead of four, for a 60 pattern double the length of the maximum tube length, with an obvious saving. 75

The three electrode tube is also advantageous for another purpose. Since both ends of the tube are always at the same potential, it is possible to pass rarefied gas through the tube from end to end, without danger of forming a wasteful by-pass for the current through gas that extends out of the tube and between its ends. I have found that a brilliant display of changing hues can be obtained by causing a constant stream of gas of varied composition to pass through the tube 11. For example, I mix an inert gas such as neon with small proportions of mercury vapor, or chlorine, or nitrogen, and successively pass these various mixtures through the tube 11; these various mixtures are then sucked by a vacuum pump to maintain the desired degree of rarefaction, and 100

the inert gas is purified and passed back to the original storage space.

One mechanism for accomplishing this process is merely schematically disclosed; 5 but obviously other forms can be used; or in fact, the process can be produced manually.

A container 15 serves as a reservoir for an inert gas which forms the base of all of the gas mixtures used in the device. Furthermore, 10 there are a plurality of other containers, 16, 17, 18, 19, 20, which can be smaller than container 15, and which hold the gases used for the mixture. Such gases can be chlorine, nitrogen, mercury vapor, 15 or the like, which either independently produce different colored effects, or do so in conjunction with the inert gas from container 15. The mercury container 16 can be heated as by coil 21 to produce the desired 20 mercury vapor.

The mechanism 22 can be used for mixing the gases. It can consist of a rotary valve member 23 or other distributing valve or valves which is driven at any desired speed 25 so as to permit gas from container 15 to pass successively through the containers 16 to 20. Thus a manifold 24 connects one side of each container with the outlet of container 15; the other side of each container 30 leads to an air tight cylinder 25 in which valve 23 rotates. This valve has a radial opening 26 sweeping past the various container outlets, and serves to pass the gas axially through bore 27 and conduit 28 to 35 one end of tube 11. It is evident that as valve 23 rotates, the inert gas from container 15 passes in succession through the various containers 16 to 20 to take up a small portion of gas from them. The current 40 in passing through these gases of varying composition, produces a vari-colored effect.

The gases pass through the tube and through a suitable pump 29, provided for maintaining the gases at the desired low 45 pressures. Thence the gases pass through the purifier 30, where the gas content taken from containers 16 to 20 is absorbed or otherwise eliminated. The purified inert gas then passes back into container 15.

50 It is difficult adequately to describe the color effects produced by this form of tube. There is a constant succession and blending of colors, with a brilliance that can be compared with that of a rainbow. These colors 55 travel through the tube 11, the speed depending upon the speed of the mixer mechanism 22. Since both ends of tube 11 are at the same potential, no current can be shunted wastefully through the mixer 60 mechanism 22 and the pump 29.

Although it is possible to provide a mixer 65 22 for each tube 11 that is used in a complete assemblage or sign, yet I can make the mixer perform its function for a plurality of tubes. This is possible by inserting a dis-

tributor valve 31 or other distributing valve or valves in the line to the tube intake. This distributor has a rotary valve element 32 that serves to connect any one or a few of the total number of tubes such as 11 with 70 the conduit 28. The mechanism is merely diagrammatically indicated; it is shown as connecting axially with conduit 28, and as having a plurality of radial valve openings 33 that serve to complete the connection to 75 the various tubes 34, 35. The distributor 31 and mixer 22 can be rotated by the same source, although the speeds need not be the same.

The idea of using several varieties of 80 gases alternately active can be utilized in other ways. Thus in Fig. 2, a series of tubes 36, 37, 38 is shown, paralleling each other. These tubes can be of different colors, and a distributor switch 39 can be 85 used to render any combination of them active, one tube at least, out of the series of tubes, although not necessarily the same one, being energized for all switching positions. In this way, various color combinations can be secured, since but three primary 90 colors are needed to obtain all colors of the spectrum.

The mode of operation of my invention 95 is self-evident from the foregoing. Variations in composition of the gas in the tube 11 are effected, either at a rapid rate or at a slow rate; and in so doing, the desired color play is obtained by the passage of current through the gases. Varying effects 100 can also be made by varying the density of the electric current supply.

I claim:

1. The process of obtaining vari-colored 105 luminous effects, which comprises passing a rarefied gas of varying composition through a tube, and applying a suitable high potential across at least a portion of the space in the tube.

2. The process of obtaining vari-colored 110 luminous effects, which comprises passing a rarefied gas having varying constituents through a tube, and applying a suitable high potential across at least a portion of the space in the tube.

3. The process of obtaining vari-colored 115 luminous effects, which comprises mixing an inert gas with one or more constituent gases, varying the constituents cyclically, passing the mixture thus varied through a 120 tube, and applying a suitable high potential across at least a portion of the space in the tube.

4. In combination, a tube, means for passing a rarefied gas of varying composition 125 through the tube, and means for applying a suitable high potential across at least a portion of the space in the tube.

5. In combination, a tube, means for passing a rarefied gas having varying constitu- 130

ents through the tube, and means for applying a suitable high potential across at least a portion of the space in the tube.

6. In combination, a tube, means for maintaining a low pressure in the tube, means for electrically energizing said tube, and means for mixing an inert gas cyclically with other gases and for passing said cyclically variable gas through the tube.

10 7. In combination, a tube, means for maintaining a low pressure in the tube, means for electrically energizing said tube, means for mixing an inert gas cyclically with other gases and for passing said cyclically variable gas through the tube, and means for recovering the inert gas from the mixture after it has passed through the tube.

15 8. In combination, a series of tubes, a mixer for obtaining a current supporting gas of varying constituents, a distributor for passing said gas to said tubes in succession, and means for energizing said tube.

9. In a luminous tube device, a tube, means for electrically energizing said tube, and means for passing a rarefied gas capable of luminescence, continuously through the tube.

In testimony whereof I have hereunto set my hand.

HERMAN J. FANGER.
